Original application Feb. 28, 1966, Ser. No. 530,514, now 5
Patent No. 3,351,021, dated Nov. 7, 1967. Divided and
this application Aug. 7, 1967, Ser. No. 667,022
U.S. Cl. 92—193 10 6 Claims
Int. Cl. F04b 47/12; F16j 1/06

ABSTRACT OF THE DISCLOSURE

A free piston type plunger having an impact responsive packer section about a mid-portion thereof which is actuated to the closed or opened configuration, respectively, as the plunger is decelerated by a lower or upper stop means, respectively, of a gas lift well. The plunger includes an upper body portion and a lower body portion. A mandrel is slidably received within the lower body portion and is attached to the upper body portion. The packer section is circumferentially disposed about the lower body portion and mounted for limited movement in a manner whereby the packer is expanded radially away from the mandrel when the plunger assumes the closed configuration, and wherein the packer is retracted radially towards the mandrel when it assumes the opened configuration.

Cross reference to related applications

This is a division of Ser. No. 530,514; for "Free Piston Pneumatic Arrestor and Control System; filed Feb. 28, 1966; for applicant Earl K. Moore, Jr. now Patent No. 3,351,021; issued Nov. 7, 1967.

Background of the invention

The use of gas lifts in producing an oil well is a well known fluid recovery means and generally employs a free piston type plunger which is actuated by the pressure of the gas from the producing formation so as to cyclically cause the piston within the tubing string to lift a slug of liquid from the oil bearing formation to a point of collection above the ground level. The free piston must accordingly reciprocate within the tubing string from one extremity thereof to the other. Generally, the pressure provided by the gas phase of the oil-gas mixture will build up in magnitude over a period of time, and at a predetermined lapse of time, a motor valve control means located at the outlet end of the tubing string will be actuated, usually in response to a timer mechanism, and generally predicated upon the known history of the well, so as to open the motor valve which permits flow from the outlet end of the tubing string, thereby establishing a pressure differential across the plunger, and accordingly allowing the plunger to move upwardly through the tubing string, thereby bringing with it a slug of liquid. When the plunger reaches the top of the tubing string the upward movement thereof is arrested and the motor valve closed. Soon thereafter the pressure across the plunger will equalize, and the plunger will fall by gravity to an abutment means located in the bottom of the eductor tube or tubing string, whereupon the plunger will then rest against the lower abutment means until the pressure has again built up to a suitable value, whereupon the motor valve will again open and the cyclic process will start over again.

A primary problem which has been recognized in conjunction with plunger lift apparatus is that the plunger in abutting the arresting apparatus located in the lubricator is subjected to a sudden deceleration. This deceleration, in the past art, is generally provided by a bumper pad and spring arrangement. Such an arrangement generally causes the spring to stack at a high rate, thereby causing the

2

plunger to receive a severe shock each time it arrives into the lubricator. In a relatively short period of time this operation results in damage to the plunger and accordingly a malfunction in its performance.

Summary of the invention

It is therefore a primary object of the present invention to provide a free piston type plunger, sometime also called a "traveling plunger," or simply a "plunger," which has an expandable packer section that sealingly cooperates with a tubing wall of a gas well in a manner to improve the flow of fluid from the well.

Another object of the present invention is to provide a plunger having an expandable packer section which is outwardly expanded to enable the plunger to assume the fluid lifting configuration, and which is inwardly contracted to enable the plunger to free-fall through a column of fluid.

A further object of the present invention is to provide a free piston associated with a gas lift well with a packer section which is actuated from the sealed to the unsealed condition, and vice versa, by the action of a centrally located longitudinally extending mandrel.

A still further object of this invention is to provide a free piston or plunger that incorporates a unique packer section thereon that retracts upon impact within the lubricator and expands upon impact with the lower bumper pad.

The above objects are attained in accordance with the present invention by the provision of a free piston type plunger fabricated in a manner essentially as outlined in the above abstract, and as defined by the annexed claims.

The various features of novelty which characterize my invention is particularly pointed out in the claims that form a part of this specification. A complete understanding of this invention may be had from the following detailed description and the accompanying drawings referred to therein, illustrating the novel features by which the above objects set forth above are carried out.

In the drawings:

FIGURE 1 is an enlarged elevational view showing the plunger of the present invention;

FIGURE 2 is another view of the device of FIGURE 1, and shown in a different operative condition as compared to FIGURE 1;

FIGURE 3 is a cross-sectional view of the device seen in FIGURES 1 and 2;

FIGURE 4 is a cross-sectional view taken along lines 4—4 of FIGURE 3; and

FIGURE 5 is a perspective view of one of the segments of FIGURES 1 through 4.

Referring now to the drawings in greater detail, the invention as illustrated therein disclosed a traveling plunger, or free piston, 200 which is intended to be placed in an eductor tube, or oil well tubing, where the plunger reciprocates from a lowermost position deep within the earth to an uppermost position above the surface of the earth, all in a manner as explained in the above parent patent application.

The instant novel device may also be used in applications where the free piston 200 is cycled occasionally so as to remove paraffin or gyp from the tubing string, for lowering gas-oil ratios, to extend the flowing life of a free flowing well, to increase efficiency on gas lift, for unloading gas wells, and to minimize emulsion.

Looking now to the details of FIGURE 1 in conjunction with the remaining figures of the disclosure, there is seen therein a pneumatically driven plunger or free piston 200 having a metal packer section 202 about the mid-portion thereof comprised of three individual metal packer segments 204 retained in place by upper body portion 206 and slip ring 205. Lower body portion 210 carries a mandrel 212 telescoped therein that threadedly engages

upper body portion 206 as indicated by numeral 213. The mandrel and upper body portion are pinned together at 214 so as to maintain upper body portion 206 and the mandrel 212 rigidly attached together. Lower body portion 210 telescopingly fits about the mandrel 212 and is adapted to reciprocate within the annulus 230 formed between the upper body portion 206 and the upper extremity of the mandrel.

The mandrel maintains the metal packer section and the slip ring in proper alignment with the remaining structure. The lower portion of the mandrel is provided with an enlargement 220 that provides a lower abutment means and cooperates with enlarged counter bore of the lower body at 224 that accordingly provides a stop means for the shoulder 222 of enlarged portion 220. The slip ring 205 is pinned to the mandrel by pin 226 which is received within an aperture that is drilled diametrically through the slip ring and mandrel. The pin 226 is adapted to carry the slip ring 205 along with the mandrel within the limits provided by the upper and lower extremities of slot 228 located in the second diameter 211 of the lower body portion 210.

The lower body portion 210 is further provided with a third reduced diameter portion 209 that is adapted to carry the metal packer section 202 about the outer periphery thereof. The third reduced diameter 209 is provided with a groove 240 that is adapted to cooperate with a lug 242 located on the inner periphery of the metal packer section. The lug 242 provides a seal to prevent gas flow through the tool and is adapted to reciprocate between the lower and upper extremities of the groove 240. The third reduced portion of the lower body portion is provided with apertures 244, 246 equally spaced about the outer periphery thereof and in alignment with similar apertures located within each segment of the metal packer section as amply illustrated by numerals 244', 246'. The aligned apertures provide a chamber within which a compressed spring 248 is located. The spring is maintained in compressed condition so as to resiliently urge the metal packer segments in an expanded direction radially away from the reduced diameter portion 209. The upper extremity of the mandrel 212 is provided with two dimples 252, 254 that cooperate with spring loaded ball 256 located within aperture 258 that resiliently holds the mandrel 212 in one of the two positions relative to the upper body portion 206. The spacing between dimples 252, 254 is equal in length to the length of travel permitted by slot 228, groove 240, and annulus 230.

The upper body portion 206 has a first counter bore 270 and a second counter bore 272 that are tapered together at 274 and provided with a shoulder at 276. The annular shoulder 276 provides an abutment for the annular shoulder 207 formed between the lower body portion fourth reduced diameter 208 and the lower body portion third reduced diameter 209.

The segments of metal packer 202 are provided with a lip at 282 and are tapered at 280 so as to cooperate with the upper body portion at second counter bore 272 in a manner to be urged from an expanded to a retracted position as the metal packer section reciprocates longitudinally of the lower body portion third reduced diameter 209. The lower extremity of each metal packer segment 290 is retained in proper position by the slip ring 205 which is provided with a taper 260 between cylindrical face 262 and 264 so as to urge the metal packer section from an expanded to a retracted position in a manner similar to the before described action in conjunction with lip 282 as it travels longitudinally along the third reduced diameter 209 of the lower body portion.

The segments 204 of the metal packer section 202 are fabricated so as to provide an upper and lower recess 216, 217, that receives upper and lower fingers 218, 219 respectively to thereby provide a tortuous path for any fluid flowing across the metal packer section of the tool and accordingly provide an effective seal. The metal packer

section is provided with ribs 266 that are adapted to ride against the inside surface education tube of the well and accordingly provide a sealed relationship between the pneumatically driven plunger and the wall of the education tube.

In operation, the pneumatic plunger will be resting on the bottom bumper of the education tube (not shown) and the metal packers section thereof will be in expanded condition and accordingly in sealing relationship with the inside wall of the education tube. When the motor valve (not shown) above the surface of the ground level is moved to the open position, the pressure differential produced across the plunger will drive the plunger in an upward direction, whereby the plunger will accordingly lift any fluid contained above the plunger and within the education tube due to the sealing relationship between the packer and the tube. During the travel of the plunger from the bottom bumper to the upper pneumatic, the metal segments 204 of the metal packer section 202 will ride against the inner peripheral surface of the education tube and provide an effective seal therewith. When the plunger reaches the upper limits of the education tube and enters the lubricator, the upper body portion 206 will strike the bumper pad or upper stop means, and accordingly the plunger will be rapidly decelerated to a complete stop. The momentum of the plunger will drive the packer segments 204 and the lower body portion 210 in an upward direction relative to the mandrel, the upper body portion 206, and the slip ring 205. The metal segments, because of the cooperation between the upper tapered surfaces 274, 280 and the lower tapered surfaces 260, 261, will assume the retracted position in opposition to the resilient springs 248. Since the plunger is now of reduced diameter, and accordingly no longer provides a sealed relationship in conjunction with the education tube, the plunger will now be free to fall by gravity to the bottom of the education tube where it will then strike the bottom bumper or stop means. The enlarged lower mandrel abutment 220 will receive the blow from the bottom bumper, whereupon the packer section and lower body portion 210, because of its inertia, will continue to travel relative to the mandrel and accordingly will return to the expanded position which permits tapered portion 280, 261 of the packer segments to be driven downwardly with respect to the adjacent tapered portions whereby the packer segments are again in expanded position and accordingly in sealed relationship with the education tube, whereupon the traveling plunger 200 is then ready for its next cycle of operation.

The novel traveling plunger, because of the retractable spring loaded segments, rides across the pipe joints of the education tube with a minimum wear since the segments of the metal packer section are free to expand and retract in conformity to the inside diameter of the education tube through which it is traveling. Hence the present novel plunger provides for a long life because of the lack of criticality between its outside diameter as compared to the diameter of the education tube. The novel plunger may be used in any existing gas lift installation, and while it is of rugged construction, the novel plunger is preferably used in conjunction with the pneumatic arrestor described in Patent No. 3,351,021, issued Nov. 7, 1967. This particular pneumatic arrestor is preferred because its improved pneumatic action lengthens the usable life of any plunger.

I claim:

1. A free piston type traveling plunger comprising an upper body portion and a lower body portion; a mandrel slidably received within said lower body portion and attached to said upper body portion; said lower body portion having a portion thereof received within said upper body portion; a packer section mounted for limited movement and circumferentially disposed about said lower body portion;

means responsive to deceleration located at each extremity of said packer section for expanding said packer section radially away from said mandrel when said traveling plunger is abruptly decelerated during downward travel, and for retracting said packer section radially towards said mandrel when said traveling plunger is abruptly decelerated during upward travel thereof.

2. The traveling plunger of claim 1 wherein; said mandrel includes a free end and a fixed end; 10 said upper body portion being rigidly attached to said fixed end;

said packer section including a series of segments circumferentially disposed about said lower body portion and displaced in interlocking relationship with 15 respect to each other; and means urging said segments radially outward from said lower body portion.

3. The plunger of claim 1 wherein said means responsive to deceleration includes a tapered end portion at 20 each end of said packer section located about the outer periphery thereof, and a similar tapered portion located on the lower extremity of said upper body portion that cooperates with one of said tapered end portions of said sections;

a slip ring attached to said mandrel and including a tapered portion that cooperates with the other of said tapered portions of said packer section, whereby:

impact of said upper body portion and impact of said 30 mandrel against a stop means provides for the above recited retracting and expanding of the packer section.

4. The plunger of claim 1 wherein said upper body portion is rigidly affixed to said mandrel; said upper body 35 includes an outwardly tapered lower portion peripherally enclosing an upper portion of said packer section and adapted to retract said packer section;

means including a slip ring attached to said mandrel and including an inwardly tapering upper portion 40 peripherally enclosing a lower portion of said packer section; said slip ring adapted to retract said packer section;

said lower body portion being slidably received within 45 said packer section and slidably enclosing a portion of said mandrel;

said mandrel having a lower portion thereof extending below said lower body portion, whereby: impact of said upper body portion and impact of said 50 depending lower mandrel portion provide for the before stated function of expansion and retraction of the packer section.

5. The plunger of claim 1 wherein said packer section includes a multiplicity of interlocking segments circumferentially disposed about said lower body portion;

said packer section including an upper end portion and 55 a lower terminal end portion;

said upper end portion having means forming an upwardly and inwardly sloped portion; said lower terminal end portion having means forming a downwardly and outwardly sloped portion; said upper body portion including a circumferentially disposed skirt which receives said upper end portion therein;

said mandrel including a slip ring attached thereto and circumferentially disposed in slidable relationship about said lower body portion and said lower terminal end;

said slip ring further including an upwardly and inwardly depending portion which cooperates with said lower terminal end, whereby:

the sloped portions of said slip ring, said upper end portion, said lower terminal end portion, and said skirt jointly cooperate to provide the recited function of the means responsive to deceleration.

6. The plunger of claim 1 wherein said packer section includes a multiplicity of interlocking segments; each segment being longitudinally disposed with respect to said mandrel, means for radially biasing each segment outwardly from said mandrel:

each segment including upper and lower depending end portions which cooperate with said means responsive to deceleration, and spaced apart edge portions;

one edge portion having means forming recesses therein, the spaced apart edge portion having means forming depending fingers thereon, said fingers of one segment being received by said recess of an adjacent segment to thereby provide a tortuous flow path across the plunger when the packer is in the expanded configuration.
